UNITED STATES PATENT OFFICE.

CLAUDE BROWN, OF CHAPEL HILL, TENNESSEE.

SANITARY MOUTHPIECE FOR TELEPHONES.

1,259,481.

Specification of Letters Patent. Patented Mar. 19, 1918.

Application filed May 17, 1917. Serial No. 169,153.

To all whom it may concern:

Be it known that I, CLAUDE BROWN, a citizen of the United States, residing at Chapel Hill, in the county of Marshall, 5 State of Tennessee, have invented a new and useful Sanitary Mouthpiece for Telephones; and I do hereby declare the following to be a full, clear, and exact description of the invention, such as will enable others 10 skilled in the art to which it appertains to make and use the same.

The present invention relates to a disinfecting attachment for the mouthpieces of telephone transmitters, and has for its object 15 to provide a device of this character which embodies novel features of construction whereby a supply of disinfectant is automatically fed to the mouthpiece as required, thereby maintaining the same at all 20 times in a sanitary condition so that there will be no danger of the transmission of diseases through the use of the telephone by different people.

Further objects of the invention are to 25 provide a telephone mouthpiece attachment of this character which is comparatively simple and inexpensive in its construction, which can be readily applied to the telephone without necessitating any changes in 30 the construction thereof or without interfering in any manner with the operation of the telephone, which has a neat and attractive appearance, and which will act in an effective manner to prevent the telephone 35 mouthpiece from serving as a carrier of diseased germs.

With these and other objects in view, the invention consists in certain novel combinations and arrangements of the parts as will 40 more fully appear as the description proceeds, the novel features thereof being pointed out in the appended claims.

For a full understanding of the invention, reference is to be had to the following description and accompanying drawings, in 45 which:—

Figure 1 is a vertical sectional view through a conventional telephone mouthpiece provided with a sanitary attachment 50 constructed in accordance with the invention.

Fig. 2 is a detail perspective view of the split clamping ring removed from the mouthpiece.

Fig. 3 is a detail perspective view of the

upper end of the upper tubular member through which passes the absorbent wick.

Corresponding and like parts are referred to in the following description and indicated in all the views of the drawings by 60 the same reference characters.

For the purpose of illustration the invention is shown as applied to the mouthpiece 1 of a conventional telephone transmitter A which is mounted upon a suitable support 65 or base B. The mouthpiece 1 is of the conventional construction, being flared outwardly and having the reduced end thereof fitted removably upon the front of the transmitter. A layer 2 of some absorbent material such as felt is applied to the side walls of the mouthpiece 1 on the interior thereof, said felt being retained in position against the side walls by a foraminous shell or cage 3 which has a shape corresponding to that 70 of the interior of the mouthpiece, the outer edge of the retaining cage being substantially flush with the outer edge of the mouthpiece when the device is in operative 75 position. The cage 3 can be very conveniently formed from woven wire fabric.

A split binding ring 4 which has a channel shaped cross section is applied to the edge of the mouthpiece 1 and serves to hold the felt retaining cage 3 securely in proper 85 position within the same. The ends of the split binding ring may be held together in any suitable manner, although in the present instance they are shown as provided with ears 5, said ears being connected by a 90 clamping bolt 6. With this construction it will be obvious that by tightening the clamping bolt the split binding ring can be drawn tightly around the edge of the telephone mouthpiece 1. Hingedly connected 95 at 7 to the split binding ring 4 is an upper tubular member 8 which has a telescoping connection with a lower tubular member 9, said tubular member 9 being hingedly connected at its lower end, as indicated at 10, 100 to a disinfectant receiving reservoir 11 which may be secured to the base B by suitable fastening means 12. A wick 13 extends through the telescoping tubular members 8 and 9, the upper end of the wick being held 105 in contact with the absorbent lining 2 of the mouthpiece 1, while the lower end of the wick extends downwardly into the disinfectant within the reservoir 11. The disinfectant from the reservoir is thus fed by 110

2
capillary attraction to the felt lining 2 of the mouthpiece, so that the said lining is at all times partially saturated with disinfectant, thereby rendering the mouthpiece 5 sanitary and enabling it to be used without danger of becoming infected with some disease.

The hinged end of the outer tubular wick receiving member 8 terminates in a resilient finger 14 which is curved laterally and extends into the mouthpiece, said finger serving to brace the end of the wick tightly against the absorbent lining 2 of the mouthpiece. At this point the inner flange of the 10 binding ring 4 is cut away, as indicated at 4^a, and the edge of the felt retaining cage 3 may also be notched, so that the end of the wick can be held in a direct engagement with the felt 2, thereby enabling a sufficient 15 quantity of disinfectant to be fed by capillary attraction from the wick to the felt lining. The hinged end of the lower tubular wick receiving member 9 terminates in a curved neck 9^a which extends downwardly 20 through a notch 15^a in the edge of a cover 15 which normally closes the top of the reservoir 11. The extensible construction 25 of the wick receiving tube and the hinged connections between the ends of the wick receiving tube and the respective elements 30 to which they are attached enable the device to be readily adjusted to fit different telephones, since the wick receiving tube can be lengthened or shortened, and also arranged at different angles, as may be necessary.

Having thus described the invention, what I claim as new and desire to secure by Letters Patent, is:—

40 1. The combination with a telephone mouthpiece, of an absorbent lining applied to the side walls thereof, retaining means for holding the absorbent lining in position, a disinfectant reservoir, an extensible wick 45 receiving tube formed in telescoping sections which are loosely connected to the retaining means and the reservoir, respectively, and a wick extending through the wick receiving tube for feeding disinfectant 50 by capillary attraction from the reservoir to the absorbent lining.

2. The combination with a telephone mouthpiece, of an absorbent lining applied

to the side walls thereof, a foraminous cage 55 fitted over the lining for holding it in position, a binding ring applied to the edge of the mouthpiece and engaging the retaining cage, a reservoir, a wick receiving tube leading from the reservoir to the binding ring, and a wick extending through the tube for 60 supplying disinfectant by capillary attraction from the reservoir to the absorbent lining.

3. The combination with a telephone mouthpiece, of an absorbent lining applied 65 to the side walls thereof, retaining means for holding the lining in position within the mouthpiece, a disinfectant receiving reservoir, a wick receiving tube extending from the reservoir to the retaining means for the 70 absorbent lining and having a spring arm at the outer end thereof, and a wick extending through the wick receiving tube for feeding disinfectant by capillary attraction from the reservoir to the absorbent lining, the 75 spring arm at the outer end of the wick receiving tube serving to hold the end of the wick in engagement with the absorbent lining.

4. The combination with a telephone 80 mouthpiece, of an absorbent lining applied to the side walls thereof, a foraminous retaining cage fitted over the absorbent lining, a split binding ring applied to the edge of the mouthpiece for holding the retaining 85 cage in position, a disinfectant receiving reservoir, an extensible wick receiving tube formed in telescoping sections which are connected to the binding ring and reservoir, respectively, the outer end of the wick receiving tube being formed with a spring 90 arm, and a wick extending through the wick receiving tube for feeding disinfectant by capillary attraction from the reservoir to the absorbent lining, the spring arm at the 95 outer end of the wick receiving tube serving to hold the end of the wick in engagement with the absorbent lining.

In testimony whereof I have signed my name to this specification in the presence of 100 two subscribing witnesses.

CLAUDE BROWN.
